(57) **CLAIM**

The ornamental design for an actuator cap, as shown and described.

DESCRIPTION

The nature of this product is as an actuator cap for an aerosol container for dispensing materials such as aerosolized insect repellents, insecticides, cleaners, and fragrances.

FIG. 1 is a left, top, frontal perspective view of an actuator cap embodying our new design;

FIG. 2 is a front elevational view thereof;

FIG. 3 is a rear elevational view thereof;

FIG. 4 is a left side elevational view thereof, the right side elevational view thereof being the mirror image thereof;

FIG. 5 is a top plan view thereof; and,

FIG. 6 is a similar view to that of FIG. 1, except that the FIG. 1 actuator cap is now shown with the environment of a container.

The broken line representation of a container environment in FIG. 6 is for purposes of illustration only and forms no part of the claim.
